UNITED STATES PATENT OFFICE.

CLARENCE B. FOWLER, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,371,749.

Specification of Letters Patent. Patented Mar. 15, 1921.

Application filed January 24, 1919. Serial No. 272,798.

To all whom it may concern:

Be it known that I, CLARENCE B. FOWLER, a citizen of the United States, residing at New York, in the county of New York, State of New York, have invented certain new and useful Improvements in Telephone-Exchange Systems, of which the following is a full, clear, concise, and exact description.

10 This invention relates to telephone exchange systems and more particularly to a line circuit for use in such systems.

It is the object of the invention to improve the signaling between a subscriber 15 and the operator in a central office telephone exchange system.

In accordance with a feature of the invention, means is provided associated with the line circuit, whereby the operation of 20 the generator of the substation may be utilized to control in the first instance, a line signal indicating that the line is a calling line, and subsequently a supervisory signal associated with an operator's cord circuit to 25 indicate that a disconnection is desired. In accordance with this feature of the invention a relay, which is responsive to alternating 30 signaling current, is arranged to coöperate with a relay normally disconnected from the line to control a supervisory signal connected with the operator's connecting circuit when the connecting circuit is associated 35 with the subscriber's line. This and other features of the invention not specifically referred to above will be apparent from the following specification.

The drawing shows diagrammatically a 40 telephone line circuit and a portion of an operator's cord circuit adapted to coöperate therewith. It is thought that the invention may be best understood from the following description of the operation of the circuit shown in the drawing.

The subscriber at substation A, desiring 45 to initiate a call, removes the usual telephone receiver from the hook switch and operates the magneto generator indicated at 1. The operation of the generator impresses alternating signaling current on the following circuit: from one terminal of the generator 1 to one conductor of the line 2, through the left-hand winding of the relay 3, back over the other conductor of the line 2 to the other terminal of the generator.

The relay 3 in operating closes a locking circuit for itself, which may be traced from battery through the right-hand winding of the relay 3, through the normal contact of the jack 9, outer armature and contact of relay 3 to ground. The relay 3 also closes 55 a circuit for the line signal, which may be traced from battery, through the line lamp 5, left-hand armature and normal contact of the relay 4, inner armature and contact of the relay 3 to ground. The operator, 60 upon observing the illumination of the signal 5, inserts the plug 8 of one of a plurality of cord circuits at her position into the jack 9. The insertion of the plug 8 opens the normal contact of the jack, which was 65 included in the locking circuit of the relay 3, causing the release of such relay. Shortly thereafter the alternate contact of the jack is made, thus preparing a circuit for the 70 slow-to-operate relay 4 upon the subsequent 75 energization of the relay 3.

It will be observed that until the energization of the relay 4, no potential is present upon the sleeve of the jack, and consequently, the insertion of the plug 8 into the 80 jack 9 will have no effect upon the supervisory lamp 6. The operator, upon ascertaining the desired number through the actuation of listening key 10 establishes a connection in the usual manner. At the termination of the conversation the subscriber A will again operate the generator 1 to indicate that a disconnection is desired, or in telephone parlance the subscriber A will "ring off." In response to this operation of 90 the generator 1, the relay 3 will be energized as before described, but since at this time the plug 8 is in the jack 9 the following circuit will be closed, from battery through the relay 4, through the alternate contact 95 of the jack 9, contact and outer armature of the relay 3 to ground. The operation of the relay 4 will prevent the display of the line signal 5 as a circuit therefor is opened at the left-hand armature and contact of the relay 4. At its inner right-hand armature, the relay 4 closes a locking circuit for the relay 3, which may be traced from battery through the right-hand winding of the relay 3, contact and inner right-hand armature of the 100 relay 4 to ground.

A circuit for the supervisory lamp 6 will be closed which extends from battery

through the supervisory signal 6, sleeve of the plug 8, sleeve of the jack 9, outer right-hand armature and contact of the relay 4 to ground. The operator, observing the dis-
5 play of the supervisory signal 6, will remove the plug 8 from the jack 9, disconnecting the previously established connection and restoring the apparatus associated with the subscriber's line to normal, ready for use in
10 connection with another call.

Inasmuch as it is contemplated that the line circuit of the invention may terminate at an exchange equipped with cord circuits arranged for common battery working, there
15 is inserted in the line intermediate the connecting point of the line relay 3 and the jack 9 a pair of condensers 7. These condensers prevent the operation or locking up of relay 3 by battery connected across the ring and
20 tip conductors of the cord circuit when the plug 8 is inserted in the jack 9.

What is claimed is:

1. In a telephone exchange system, a line circuit, a link circuit for connection therewith, a locking relay associated with the line, a signaling device controlled thereby, means responsive to the connection of the link circuit with the line circuit to open the locking circuit of and thereby release the
25 relay, and means coöperating therewith to prepare another locking circuit for use by the relay upon a subsequent energization thereof.

2. In a telephone exchange system, a line circuit, a link circuit for connection therewith, a locking relay associated with the line, a signaling device controlled thereby, two locking circuits for the relay, and means controlled by the connection and dis-
35 connection of the link circuit with the line circuit for determining the locking circuit to be used by the relay.

3. In a telephone exchange system, a line circuit, a link circuit for connection therewith, a relay associated with the line circuit, a signaling device controlled thereby, a supervisory signaling device associated with the link circuit, means responsive to the connection of the link with the line for
45 removing the line signaling device from the control of the relay, and a circuit for the supervisory signaling device adapted to be

closed upon a subsequent energization of the relay.

4. In a telephone exchange system, a line circuit, a link circuit for connection therewith, a relay associated with the line circuit, a signaling device controlled thereby, a supervisory signaling device associated with the link, means responsive to the connection of the link with the line for removing the line signaling device from the control of the relay and for releasing the relay, additional means coöperating therewith to prepare a circuit for the supervisory signaling device, and further means responsive to a subsequent energization of the line relay during the connection to complete the operating circuit of the supervisory signaling device.
5. In a telephone exchange system, a line circuit terminating in a jack having a normally disconnected sleeve contact, a link circuit terminating in a plug for connection therewith, a relay associated with the line circuit, a signaling device associated with the link circuit, and means jointly controlled by the connection of the plug with the jack and by an energization of the relay for connecting a source of current with the sleeve contact to control the supervisory signaling device.

6. In a telephone exchange system, in combination, a telephone line terminating in a jack at a central office, a line signal therefor, means at the other end of the line for transmitting alternating current over the line for calling and for giving a disconnect signal, a link circuit terminating in a plug, a supervisory signal for the link circuit, a line relay actuated in response to the reception of a calling signal for actuating said line signal, and a second relay associated with the telephone line, but normally disconnected therefrom, coöperating with the line relay for actuating the supervisory signal when the plug of the link circuit is inserted in the jack of the line circuit to actuate the supervisory signal when a disconnect signal is transmitted over the telephone line.

In witness whereof, I hereunto subscribe my name this 16th day of January, A. D. 1919.

CLARENCE B. FOWLER.
